NURSING BOTTLE NIPPLE AND SHIELD
THEREFOR

Joseph Kronish, Mount Vernon, N. Y.

Original application January 11, 1947, Serial No. 721,607, now Patent No. 2,579,194, dated December 18, 1951. Divided and this application December 13, 1951, Serial No. 261,469

6 Claims. (Cl. 128—252)

1

My present invention relates generally to nipples for nursing bottles, and has particular reference to an improved combination of a nipple and shield.

This application is a division of my earlier-filed application for patent, Serial No. 721,607 (now Patent No. 2,579,194).

It is a general object of the invention to provide a nipple and shield which are of such construction, and cooperate in such a way, that the shield can be applied to the nipple prior to sterilization of the latter while still permitting a sterilizing medium, into which the assembly is immersed, to have free access to the surfaces of the mammilla of the nipple. If the shield and nipple are sterilized apart from the bottle, the shield is associated with the nipple not only during sterilization but remains protectively on the nipple after sterilization and during and after the application of the sterilized nipple to the bottle, until such time as the infant is to be fed. Similarly, if the so-called "terminal sterilization" procedure is followed, whereby the nipple is first placed on the bottle and then the bottle, the formula in it, the nipple and the shield are all sterilized at one time, the shield is on the nipple during sterilization and remains protectively on the nipple after sterilization until feeding time.

In accordance with my invention the nipple and shield are designed so that the shield, while in engagement with the nipple, may be selectively adjusted into either a partially applied position or a more fully applied position, and so that in the partially applied position a sterilizing passage leads through the shield into the space between the mammilla and shield while in the more fully applied position of the shield this passage is sealed off.

The present application is specifically directed to one way of achieving this result, viz., by means of an opening in the shield which lies in its entirety in such a location, relative to the nipple rim with which the shield is in engagement, that in one position of the shield the opening overlies such rim and is obstructed thereby while in the other position of the shield the opening affords access for the sterilizing medium to pass directly through it into the space surrounding the mammilla of the nipple.

Two embodiments of the invention are illustrated in the accompanying drawings, in which—

Figure 1 is a cross-sectional view of a nipple and shield constructed in accordance with the

2

invention, showing the parts in the relationship they assume during the sterilizing procedure;

Figure 2 is a similar view, showing the shield in sealing position and the nipple in association with a nursing bottle;

Figure 3 is an elevational view of the parts in the same relationship as in Figure 2, with the shield broken away to reveal the nipple in elevation;

Figure 4 is a cross-sectional view along the line 4—4 of Figure 2; and

Figures 5 and 6 are views similar to Figures 1 and 2 respectively, illustrating a modification.

Referring to Figures 1—4, the nipple 9 is of well-known kind, preferably made of rubber or its equivalent. At its rear it has an annular attachment rim 8 provided with internal screw threads 7 by means of which the nipple may be secured to the correspondingly threaded mouth 2 of a nursing bottle 1. The nipple is provided at its forward end with the conventional mammilla 5 pierced by one or more apertures. The mammilla is of lesser diameter than the attachment rim 8, as shown, and may also be of thinner and more flexible quality, as is well known.

The shield 10 is composed of relatively rigid material such as aluminum or other suitable metal, glass, or plastic or the like. It has a cup-shaped part 19 enclosing the mammilla, and a rear annular sleeve 38 adapted to engage with the attachment rim 8 of the nipple. In the embodiment illustrated, this engagement is of a screw-threaded character, the rim 8 being provided with external screw-thread projections 50 (Figure 3) and the sleeve 38 having complementary internal threads or projections.

The rim 8 of the nipple is of appreciable axial extent, and the sleeve 38 of the shield is of comparable extent. Accordingly, when the sleeve is engaged with the nipple rim it is axially movable with respect to the rim while remaining in engagement therewith. It may in fact be adjusted selectively into either of two axially displaced positions relative to the rim, one of these positions being the partially applied position of the shield shown in Figure 1, the other being the more fully applied position of the shield shown in Figures 2 and 3.

In accordance with the present invention, the sleeve 38 is provided with at least one sterilizing opening located in its entirety in a region spaced from the edge of the sleeve. There are preferably two or more openings or slots 32, as best shown in Figure 4. They are preferably extend-

ed circumferentially and arranged at equal circumferential spacing from each other. They all lie substantially the same distance in from the edge of the sleeve 38, viz., at the inner end of the sleeve, closely adjacent to the line along which the sleeve merges into the cup-shaped part 19 of the shield. In this region of the shield, on its inside surface, it is provided with an annular projection or shoulder 16 which bears down against the inner end of the attachment rim 8 when the shield is in the closed position shown in Figures 2 and 3.

When the nipple is to be sterilized the shield 10 and nipple 9 are assembled prior to immersion in the sterilizing medium (usually steam or boiling water), by placing the shield into the partial engagement with the nipple as shown in Figure 1. In this position the openings 32 lie axially offset from the attachment rim 8 thereby affording free passage for the sterilizing medium inwardly through the opening or openings 32 into the space surrounding the mammilla of the nipple. Obviously, the sterilizing medium also reaches the interior surfaces of the nipple through the rear end of the nipple. While the parts are in this "sterilizing position" they remain in association with each other and can be freely-handled as a unit.

When sterilization has been completed, the partially nested nipple and shield can be removed from the sterilizer or sterilizing bath by grasping only the shield, thus leaving the nipple surfaces sterile. The assembly may then be set aside, or may be immediately applied to a sterilized and filled nursing bottle. In the construction shown in Figures 1-4 the attachment of the nipple to the bottle is accomplished by screwing the nipple onto the threaded mouth of the bottle. This may readily be done without separating the shield from the nipple.

In the alternative, if the procedure known as "terminal sterilization" is followed, the nipple and shield are first applied to the formula-filled bottle, adjusted into the partial engagement shown in Figure 1, and the entire assembly is then subjected to sterilizing temperatures. For example, the bottle may be stood in boiling water in a covered container. The steam generated by the formula sterilizes the interior surfaces of the nipple, while the external surfaces are subjected to the sterilizing effect of the steam which passes inwardly through the shield openings 32 into the space surrounding the mammilla of the nipple. When sterilization has been completed, the shield is adjusted into the sealing position shown in Figures 2 and 3 until feeding time, when its complete removal exposes the nipple in sterile and uncontaminated state.

Regardless of which sterilizing procedure is followed, it will be observed that in the sealing position of Figures 2 and 3 the projection 16 abuts against the end of the attachment rim 8 and the openings 32 overlie and are thus obstructed and sealed off by the rim 8. The mammilla of the nipple is thus enclosed in an air-tight manner, and since the parts are so designed that the cap of the shield simultaneously abuts the end of the mammilla and seals off the aperture in it, the bottle may safely be left in this sealed condition for any length of time without danger of exposing the sterilized nipple or the content of the bottle to the atmosphere and without danger of leakage of the content of the bottle.

In the embodiment shown in Figures 5 and 6, the nipple is associated with the bottle in a dif-

ferent way, and the engagement between nipple rim and shield is purely frictional and devoid of screw-threadable parts. Nursing bottle 20 is tapered to a constricted neck having an annular rim or bead 42. The rim 48 of the nipple is designed to fit frictionally over bottle bead 42, as shown in Figure 6. To increase the yieldability and resilience of the nipple rim 48 an annular relieving groove 49 may be provided on the exterior of the rim.

As will be noted, the exterior of the rim 48 is unthreaded, and the interior of the shield sleeve 38 is of complementary size and contour so that a snug frictional interengagement results. As before, the nipple rim is of appreciable axial extent, and the sleeve of the shield is of comparable extent, whereby the latter may be adjusted axially on the rim and also remain continuously in engagement with the latter.

20 In other respects the nipple and shield of Figures 5 and 6 are the same as in Figures 1-4, and for this reason the same reference numerals have been applied to the mammilla 5, the internal shoulder 16 on the shield, and the sterilizing 25 openings 32. As in Figures 1-4, these openings are set back from the edge of the sleeve 38 and lie forwardly of the nipple rim 48 in the partially applied position of the shield (Figure 5) and are obstructed by the rim in the more fully applied 30 position of the shield (Figure 6).

In the sterilizing relationship of parts (Figure 5) the sterilizing medium has free access to the interior of the shield, through openings 32. After sterilization, if performed apart from the bottle, 35 the nipple-shield assembly is handled only by the shield, and the nipple may be applied to the bottle 20 by pressing it down over the bead 42, the rim 48 expanding momentarily during this procedure. As hereinbefore pointed out, an alternative sterilizing procedure involves first filling the bottle with the formula, applying the nipple and the shield and adjusting them into the sterilizing relationship (Figure 5), and then sterilizing the entire unit.

40 In the sealing relationship of parts (Figure 6) the sterilizing openings 32 are sealed off by the rim 48, and the shoulder 16 and shield end press down on the nipple rim and mammilla tip respectively to establish a protective and air-tight 45 enclosure for the nipple. When the bottle is to be used to feed the baby, the shield is completely withdrawn from the nipple.

It will be understood that the details herein 50 described and illustrated may obviously be modified in a number of respects without necessarily departing from the spirit and scope of the invention as expressed in the appended claims.

Having thus described my invention and illustrated its use, what I claim as new and desire to secure by Letters Patent is:

1. The combination with a nursing bottle nipple having an apertured mammilla and an attachment rim, of a shield having a portion enclosing said mammilla and a sleeve removably 55 engageable with said rim, said rim being of appreciable axial extent, said sleeve being of comparable axial extent and being axially movable with respect to said rim while remaining in engagement therewith, said sleeve being selectively 60 adjustable into either of two axially displaced positions relative to said rim, said sleeve having an opening therethrough located in its entirety in a region spaced from the edge of the sleeve, said opening overlying said rim and being obstructed thereby when the sleeve is in one of said 65

positions, said opening lying axially offset from said rim when the sleeve is in the other of said positions, said opening in the last-mentioned position of the sleeve affording passage for a sterilizing medium inwardly therethrough into the space surrounding said mammilla.

2. In a combination nursing bottle nipple and shield, the structure defined in claim 1, said opening extending in a generally circumferential direction.

3. In a combination nursing bottle nipple and shield, the structure defined in claim 1, there being at least two of said openings arranged in circumferentially spaced relation, all lying at substantially the same distance from the edge of the sleeve.

4. In a combination nursing bottle nipple and shield, the structure defined in claim 1, the engagement between the sleeve and rim and the adjustability of the sleeve on the rim being afforded by complementary screw-thread elements formed on the sleeve and rim.

5. The combination with a nursing bottle nipple having a forward apertured mammilla and a rear attachment rim, said mammilla being of lesser diameter than the rim, of a shield having a forward part enclosing said mammilla and a rear sleeve removable applicable to said rim, said sleeve and rim being provided with complementary screw-thread parts so that by a screwing and unscrewing of the sleeve the shield

5

may be selectively set into either a partially applied or a more fully applied position relative to said rim, said sleeve being provided with at least one opening therethrough which lies in its entirety forwardly of the rim in the partially applied position of the shield and which is obstructed by the rim in the more fully applied position of the shield, said opening establishing a sealable sterilizing passage through the shield to the space between the shield and the mammilla enclosed thereby.
